CHILD'S FOLDING CHAIR

Thomas E. Rost, Hazel Crest, Ill.

Application August 22, 1956, Serial No. 42,707

Term of patent 7 years

(Cl. D15—1)

Fig. 1.

Fig. 2.

Fig. 3.

Figure 1 is a bottom perspective view of a child's chair, showing my new design, and

Figure 2 is a front perspective view thereof as the chair appears in folded condition, and

Figure 3 is a front perspective view thereof as the chair would ordinarily be seen.

I claim:

The ornamental design for a child's folding chair, as shown.
